UNITED STATES PATENT OFFICE.

ERNST H. HUENEFELD, OF CINCINNATI, OHIO.

DESIGN FOR A HEATING-STOVE.

SPECIFICATION forming part of Design No. 28,496, dated April 19, 1898.

Application filed December 28, 1897. Serial No. 664,123. Term of patent 14 years.

To all whom it may concern:

Be it known that I, ERNST H. HUENEFELD, of Cincinnati, State of Ohio, have invented a new and original Design for Heating-Stoves, 5 of which the following is a full, clear, and exact description, reference being had to the accompanying drawings, forming a part thereof.

In the drawings, Figure 1 is a view in side 10 elevation of a stove embodying my design, and Fig. 2 is a view in plan.

The leading feature of my design consists of a cylindrical body located exterior to an oval body and extending parallel with said 15 oval body from the plane of the top of the oval body to a point near the base thereof, the lower end of the cylindrical body curving inwardly toward and in contact with the oval body.

20 A represents the oval body, provided at a point below its top with two parallel corruga-

tions *a*, extending around the body, and at a point above its base or bottom with two similar corrugations *b*.

A cylindrical body *B*, considerably smaller 25 than the lesser diameter of the oval body, is located exterior to one end of the oval body and extends from approximately the plane of the top of the oval body to a point above the base of the latter and then curves inwardly 30 toward and in contact with said body, the cylindrical body having two corrugations or rings located approximately in line with the corrugations or rings *a* on the oval body.

What I claim is—

35 The design for a heating-stove herein shown and described.

ERNST H. HUENEFELD.
